Patented Feb. 14, 1922.

UNITED STATES PATENT OFFICE.

RALPH A. WILLIAMS AND ALBERT J. WAGNER, OF BELOIT, WISCONSIN.

SHOULDER BRACE.

1,406,795.

Specification of Letters Patent. Patented Feb. 14, 1922.

Application filed July 21, 1921. Serial No. 486,551.

To all whom it may concern:

Be it known that we, RALPH A. WILLIAMS and ALBERT J. WAGNER, citizens of the United States, residing at Beloit, in the county of Rock and State of Wisconsin, have invented certain new and useful Improvements in Shoulder Braces; and we do declare the following to be a full, clear, and exact description of the invention, such as 10 will enable others skilled in the art to which it appertains, to make and use the same.

This invention relates to improved shoulder braces, it being the principal aim of the invention to devise a device of this class 15 which is such in construction that it will effectively force the shoulder blades rearwardly and toward each other, tend to throw the chest out, brace the back, and in every way assist in maintaining this portion 20 of the body erect.

Another object of the invention is to provide a brace of this class embodying a waist encircling member carrying upstanding rods which extend upwardly over the chest and 25 have their free ends directed toward each other and terminating near the juncture of the arms and shoulder, providing an arrangement which at all times reminds the wearer that his shoulders are not being held 30 back as they should be. Hence, round-shouldered persons can have their shoulders restored to their natural or original position by making constant use of braces of such formation.

35 Another object of the invention is to provide an arrangement which includes the aforesaid upstanding arms bearing against the chest, together with means for exerting a rearward pull on these members and at 40 the same time tending to force the upper portion of the back forwardly so that the shoulder blades will be acted on in such a way as to move rearwardly and come together and assume a position which will 45 cause this portion of the body to remain erect.

A further and important object of the invention is to generally improve upon braces of this class by the provision of a structure 50 which is adapted to accomplish effective results, one which is strong and durable, and is so simple in construction that it can be manufactured and retailed at extremely low costs to all concerned.

55 Other objects and advantages of the in-

vention will be apparent during the course of the following description.

In the accompanying drawings forming a part of this specification and in which like numerals are employed to designate like parts throughout the same:

Figure 1 is a front perspective view of a person wearing our improved shoulder brace.

Figure 2 is a view looking at the back of the person and showing the elastic band which passes across the back just beneath the shoulder blades.

Figure 3 is an enlarged rear perspective view of a device constructed in accordance with this invention, showing the construction and arrangement of parts more clearly.

Referring to the drawings by numerals, 1 designates a waist-encircling belt which includes the stretchless fabric portions 2 and 75 elastic connecting portions 3. The numerals 4 designate buckles of suitable construction which are arranged approximately diametrically opposite one another in front and back to permit a double adjustment to be 80 had. Rising upwardly from and connected to this belt 1 and disposed at points approximately diametrically opposite one another are metal rods 5 which have their upper ends curved gradually inwardly toward 85 one another as indicated at 6. As before pointed out, with this arrangement the bracing members 5 when in use, and as shown clearly in Fig. 1, extend upwardly over the front portion of the body and chest and the 90 upper curved extremities rest on the chest adjacent the uppermost ribs and when drawn rearwardly or toward the body, cause the shoulders to be elevated and the shoulder blades to move rearwardly and toward each 95 other and remain in such a position as long as the device is in use. At this point, it is to be stated that the rods are preferably wrapped with fabric material 7 and suitably shaped pads 8 are arranged on the upper 100 extremities of the rods and insure comfort to the wearer. However, if the shoulders are allowed to droop forwardly as is ordinarily the case, the ends of the padded rod will inflict a slight pain upon the person for 105 the moment and remind him to straighten his shoulders.

To exert a rearward pull on the members 5 and to also tend to force inwardly on the back, we preferably make use of an adjust- 110

able elastic band 9 which is connected at its ends to the members 5 adjacent the upper ends of the latter and extends crosswise of the back at a point just beneath the shoulder blades. It is yet to be pointed out that to increase the rigidity and strength of the device and insure that it will be properly held in place, we provide the members 5 with longitudinally curved lateral extensions 10 which are connected with the sections 2 of the aforesaid belt 1, being disposed between the pieces of fabric of which these parts of the belt are composed.

In use, the belt 1 is placed about the waist 15 in the position clearly indicated in Fig. 1 and the buckles are adjusted to cause the belt to rather snugly fit the body. Then, the elastic strap or band 9 is drawn tight across the back and the members 5 are simultaneously drawn tightly against the chest and the shoulder blades forced rearwardly and toward each other. Due to the elasticity of the band 9, the back is forced slightly forward so that the entire upper portion of 25 the body is caused to assume an erect and proper position. After the device is in place, it will not interfere with free movement of the arms and will not interfere with free movement of the upper portion of the 30 body, but at the same time it will hold the shoulders back and at all times remind the wearer that the shoulders should be held in such a way.

By carefully considering the description 35 in connection with the drawings, persons familiar with devices of this class will doubtless be able to obtain a clear understanding of the invention. Therefore, a more lengthy and detailed description is 40 deemed unnecessary.

Since probably the best results may be obtained with the construction and arrangement herein shown and described, this is taken as the preferred embodiment of the 45 invention. However, we wish it to be understood that minor changes coming within the scope of the subjoined claims may be resorted to if desired.

We claim:

50 1. A shoulder brace comprising a body encircling member, a pair of upstanding

bracing members carried by said member and extending upwardly across the forward portion of the body and chest and having their upper ends directed inwardly toward each other and terminating adjacent the shoulders and bearing against the chest. 55

2. The structure set forth in claim 1, together with means for exerting a rearward pull on said bracing members and for simultaneously exerting a forward push on the back just below the shoulder blades. 60

3. A shoulder bracing device of the class described comprising a belt for encircling the waist, diametrically opposite upstanding bracing members carried by said belt and extending over the chest and terminating adjacent the clavical bones, the upper extremities of said members being curved to conform to the portion of the body against 70 which they bear, and an adjustable band connecting at its ends to said members and extending across the back adjacent the shoulder blades. 85

4. A shoulder brace comprising a pair of 75 substantially L-shaped rods, the vertical portions of which have their upper ends curved inwardly toward each other, and a body-encircling retaining band connected to the horizontal portions of said rods. 80

5. A shoulder brace comprising an adjustable waist-encircling belt, a pair of diametrically oppositely disposed vertical rods having their lower ends directed horizontally and connected to said belt, the vertical 85 portions of the rod being extended upwardly over the front portions of the body and across the chest, the upper ends of said last-named portions being curved laterally inwardly toward each other and terminating 90 adjacent the clavical bones, a covering for the vertical portions of said rods, pads on the extremities of the latter, and elastic bands extending across the back just below the shoulders, the inner ends thereof 95 being adjustably connected together and opposite ends being connected to the aforesaid vertical portions of said rods.

In testimony whereof we have hereunto set our hands.

RALPH A. WILLIAMS
ALBERT J. WAGNER
